UNITED STATES PATENT OFFICE.

WILLIAM H. BARLOW, OF GOLDFIELD, NEVADA.

GATE FOR BINS.

1,280,368.

Specification of Letters Patent.

Patented Oct. 1, 1918.

Application filed April 26, 1918. Serial No. 230,980.

To all whom it may concern:

Be it known that I, WILLIAM H. BARLOW, a citizen of the United States, residing at Goldfield, in the county of Esmeralda and 5 State of Nevada, have invented certain new and useful Improvements in Gates for Bins; and I do hereby declare the following to be a full, clear, and exact description of the invention, such as will enable others skilled in 10 the art to which it appertains to make and use the same.

This invention relates to new and useful improvements in gates for bins and has for one of its objects the provision of a device 15 of this character, which shall be simple, durable and efficient, and which may be manufactured and sold at a comparatively low cost.

Another object of this invention is the 20 provision of a plurality of doors to the chute of a bin, which doors are so arranged that the inner door is the first to occupy a closed position, thereby cutting off the supply of material in the chute and permitting 25 material in the chute to discharge therefrom prior to the closing of the remaining doors.

A further object of this invention is the 30 provision of means for raising the plurality of doors successively so as to permit materials to readily pass through the chute of the bin.

With these and other objects in view as 35 will become more apparent as the description proceeds, the invention consists of certain novel features of construction, combination and arrangement of parts as will be herein-after more fully described and claimed.

For a complete understanding of my invention, reference will be had to the following 40 description and accompanying drawing, in which:

Figure 1 is a front elevation of gates for bins, constructed in accordance with my invention, 45 Fig. 2 is a vertical sectional view of the same, and

Fig. 3 is detail sectional view taken on the line 3—3 of Fig. 2.

Referring in detail to the drawing, the 50 numeral 1 designates a frame secured to a storage bin in any well known manner and having an upwardly inclined bottom wall 2 secured thereto and extending into the bin for forming a chute. The numeral 3 indicates the front wall of the bin which terminates in a plane above the inclined wall 2

to form a passage from the bin outwardly through the frame.

A plurality of guide strips 4 are secured to the frame 1 and has slidably mounted 60 therein doors 5, 6, and 7. The doors 6 and 7 are of the same length and the door 5 is approximately one-third longer than the doors 6 and 7 to render it of greater weight. The door 5 is the inner door as will be noted 65 by referring to Fig. 2 and has its lower end beveled as illustrated at 8 to assure its cutting through the materials passing outwardly from the bin along the bottom 2 of the chute.

Angle irons 9 are secured to the doors 5 and 6 and the angled iron of the door 5 overlies the path of travel of the door 6 and the angled iron of the door 6 overlies the path of travel of the door 7. Secured to the door 7 by an eye bolt 10 is a cable 11 passing over a pulley 12 carried by the upper end of the frame for the purpose of raising the doors upwardly. As the cable is pulled, the door 7 moves upwardly and engages the angled iron 9 of the door 6 and moves the same upwardly with the door 7. Upon further movement of the doors 6 and 7 upwardly, the door 6 engages the angled iron 9 of the door 5 unseating the door 5 from the bottom wall 2 allowing the material within the bin to pass outwardly therefrom. When the cable 11 is released, the doors move downwardly and the door 5 is the first 80 to engage the bottom wall 2 stopping the flow of material from the bin.

The door 5 being the first to engage the bottom wall 2 stops the flow of material from the bin and permits any material which may be upon the bottom wall 2 to pass therefrom before the doors 6 and 7 come into engagement with the bottom wall 2, thus the doors 6 and 7 engage a smooth surface upon the bottom wall 2, thereby rendering a tight seal to the chute obviating any danger of leakage of material from the bin.

While I have shown and described the preferred embodiment of my invention, it will be understood that minor changes in construction, combination and arrangement of parts may be made without departing from the spirit and scope of the invention as claimed.

Having thus described my invention what I claim is:

A device of the character set forth comprising a frame connected to a bin, a bottom

wall connected to the frame and in communication with the bin to form a chute, a plurality of doors slidably mounted in said frame, the innermost door of the plurality of doors being of greater length than the other doors to permit said door to engage the bottom wall first to close the chute and permit the materials within the chute to pass therefrom before the remaining doors engage the bottom wall, angle irons secured to some of said doors and overlying the path

of travel of the next adjacent door to the respective door carrying the angle iron, and a cable connected to the outermost door for unseating the doors successively.

15

In testimony whereof I affix my signature in presence of two witnesses.

WILLIAM H. BARLOW.
